UNITED STATES PATENT OFFICE.

SAM HARBISON, OF KNOXVILLE, TENNESSEE.

DESIGN FOR A WRENCH.

SPECIFICATION forming part of Design No. 32,794, dated June 5, 1900.

Application filed May 7, 1900. Serial No. 15,835. Term of patent 14 years.

To all whom it may concern:

Be it known that I, SAM HARBISON, a citizen of the United States, residing at Knoxville, in the county of Knox and State of Tennessee, have invented and produced a new and original Design for a Wrench, of which the following is a specification.

This invention relates to a new and original design for a wrench; and it has for its object to provide a design of this character that shall be both useful and ornamental.

The leading feature of the design resides in the shank provided at opposite ends with approximately **U**-shaped heads or jaws, each of which is provided upon its opposite inner sides with a series of alternating **V**-shaped notches and lips, the oppositely-arranged lips and notches lying in common transverse planes.

The minor features of the design are the shank, being of a sigmoidal shape, and the terminal heads or jaws, being respectively of different sizes and arranged within the plane of the shank and each provided within the base thereof with approximately **U**-shaped pockets having curved side walls.

In the drawings, Figure 1 is a perspective view of a wrench embodying the herein-described design. Fig. 2 is an elevation thereof.

Referring particularly to the drawings, the 30 numeral 1 designates a wrench-shank having a sigmoidal curvature and provided at opposite ends within the plane thereof with approximately **U**-shaped jaws or heads 2, respectively, of different sizes. Each of the 35 said heads or jaws 2 is provided upon its opposite inner side edges with a series of alternating **V**-shaped notches and lips 3 and 4, respectively. The oppositely-located lips and notches, respectively at opposite sides of the 40 bifurcation of each head or jaw, lie in common transverse planes, or, in other words, are disposed diametrically opposite each other.

Each approximately **U**-shaped head or jaw 2 is further provided within the base of its 45 bifurcation with an approximately **U**-shaped pocket 5, having curved side walls 6.

What is claimed is—

The design for a wrench herein shown and described.

In testimony that I claim the foregoing as my own I have hereto affixed my signature in the presence of two witnesses.

SAM HARBISON.
